UNITED STATES PATENT OFFICE

1,927,687

POWER PLANT

Friedrich Kissing and Paul Hösel, Berlin-Charlottenburg, Germany, assignors to General Electric Company, a corporation of New York

Application June 15, 1932, Serial No. 617,397,
and in Germany August 26, 1931

2 Claims. (Cl. 60—95)

The present invention relates to power plants, more particularly to the kind of plants in which an elastic fluid engine such as a turbine, a generator and exciter driven thereby are arranged 5 on one shaft with a condenser and a pump for the condenser to form a constructional unit, known as a turbo-block form. In such an arrangement the condenser receives the exhaust elastic fluid from the elastic fluid engine, and 10 condensate is discharged from the condenser by means of a condensate pump. Another pump has to be provided which may be driven by the turbine shaft for circulating cooling medium, such as water, through the condenser. In installations of this kind it has been the practice 15 in some cases to drive the condensate pump by means of a transmission gearing from the turbine shaft. The arrangement of the transmission gearing in many cases causes difficulties, particularly when the pump is located below or 20 near the lower part of the condenser.

The object of the present invention is to provide an improved arrangement for driving a condensate pump or like auxiliary apparatus in power plants whereby the condensate pump can 25 be placed in any suitable position without regard to the location of the main shaft.

For a consideration of what we believe to be 30 novel and our invention, attention is directed to the following description and the claims appended thereto in connection with the drawing which forms a part of our specification.

In the drawing we have shown diagrammatically by way of example a turbine installation in 35 turbo-block form embodying our invention. 1 designates an elastic fluid turbine having an exhaust conduit 2 connected to a condenser 3. 4 is an electric generator driven by the turbine and connected to an electric line 5. 6 is an exciter for the generator.

For circulating cooling water or like cooling 45 fluid through the condenser we provide a cooling water or fluid pump 7 driven from the turbine shaft 8 through a reducing gear 9. 10 designates the condensate pump for discharging condensate of the condenser. 10^a is an outlet for discharging the cooling water from the condenser.

The arrangement so far described may be 50 considered as typical of any turbine installation in turbo-block form. Whereas heretofore it has been the practice to drive the condensate pump by means of a transmission gearing from the turbine shaft, according to our invention we provide a water turbine or like power agency 11 re-

ceiving water or like fluid from pump 7 through a conduit 12 and discharging the cooling water or fluid to the condenser through a conduit 13. Thus the reducing gear 9, the cooling water pump 7 and the water turbine 11 together form 60 in substance a means for driving the condensate pump. At least a part of the cooling medium discharged from pump 7 forms a driving medium for the power agency 11. With such an arrangement little additional power is necessary 65 for driving the cooling water pump 7. Provided on the shaft of the water turbine is another auxiliary apparatus, in the present instance shown as an auxiliary generator 14, connected to an electric line 15. This auxiliary generator 70 may serve as a house generator or the like in case the main generator 4 fails. During operation, pumping means 7 pumps cooling medium such as water from any suitable source, not indicated, to turbine 11 with respect to which the 75 cooling medium forms a driving medium. Turbine 11 discharges this medium to condenser 3. Condensate pump 10 pumps condensate from the condenser and discharges it to any suitable point, not shown in the drawing.

With our invention we have accomplished a simple and reliable arrangement for driving an auxiliary apparatus, particularly a condensate pump in an elastic fluid power plant by means 80 of a water turbine receiving its driving medium 85 from the cooling water pump.

Having described the method of operation of our invention, together with the apparatus which we now consider to represent the best 90 embodiment thereof, we desire to have it understood that the apparatus shown is only illustrative and that the invention may be carried out by other means.

What we claim as new and desire to secure by 95 Letters Patent in the United States is:

1. In a power plant, the combination of an elastic fluid turbine, a condenser connected to the turbine exhaust, a water pump driven from the turbine shaft and having an outlet connected to the condenser for forcing cooling water into the condenser, a condensate pump having an inlet connected to the condenser for discharging condensate therefrom, and means for driving the condensate pump comprising a water turbine connected between said water pump and the condenser and driven by the water discharged from the water pump.
2. In a power plant, the combination of an

elastic fluid turbine, a condenser connected to the turbine exhaust, a water pump driven from the turbine shaft and having an outlet connected to the condenser for forcing cooling water into the condenser, a condensate pump having an inlet connected to the condenser for discharging condensate therefrom, a water turbine con-

nected between said water pump and the condenser and driven by the water discharged from the water pump for driving the condensate pump, and a dynamo electric machine coupled with the water turbine.
